CLAIM

The ornamental design for a bottle, as shown and described.

DESCRIPTION

FIG. 1 is a front elevation view of a bottle showing my new design;

FIG. 2 is a left side elevation view thereof;

FIG. 3 is a rear elevation view thereof; and,

FIG. 4 is a right side elevation view thereof.

All surfaces not shown form no part of the claimed design.

The broken line showing of a bottle is included for the purpose of illustrating only and forms no part of the claimed design.
